(57) **CLAIM**

The ornamental design for an earbud case as shown and described.

DESCRIPTION

FIG. 1 is a perspective view of an earbud case in a closed position, partially from the front side of the earbud case, partially from the right side of the earbud case, and partially from the top of the earbud case;

FIG. 2 is a top view of the earbud case of FIG. 1;

FIG. 3 is a front view of the earbud case of FIG. 1;

FIG. 4 is a right side view of the earbud case of FIG. 1;

FIG. 5 is a left side view of the earbud case of FIG. 1;

FIG. 6 is a back view of the earbud case of FIGS. 1; and

FIG. 7 is a bottom view of the earbud case of FIG. 1.

FIG. 8 is a perspective view of an earbud case of FIG. 1 in an open position, partially from the front side of the earbud case, partially from the right side of the earbud case, and partially from the top of the earbud case;

FIG. 9 is a top view of the earbud case of FIG. 8;

FIG. 10 is a front view of the earbud case of FIG. 8;

FIG. 11 is a right side view of the earbud case of FIG. 8;

FIG. 12 is a left side view of the earbud case of FIG. 8;

FIG. 13 is a back view of the earbud case of FIG. 8; and,

FIG. 14 is a bottom view of the earbud case of FIG. 8.

The broken lines in the figures depict portions of the earbud case that form no part of the present design.
